(57) **CLAIM**

The ornamental design for a golf ball striker, as shown and described.

DESCRIPTION

FIG. 1 is a perspective view of a golf ball striker;

FIG. 2 is a side view thereof;

FIG. 3 is a right view thereof;

FIG. 4 is a left view thereof;

FIG. 5 is a top view thereof; and,

FIG. 6 is a bottom view thereof.

Any broken lines in all views are included for the purpose of illustrating portions of the golf ball striker and form no part of the claimed design.

1 Claim, 4 Drawing Sheets
